(57) **CLAIM**

We claim the ornamental design for a protective case for a power tool, as shown and described.

DESCRIPTION

FIG. 1 is a top perspective view of a protective case for a power tool of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The ornamental design which is claimed is shown in solid lines in the drawings. Any broken lines in the drawings are for illustrative purposes only and form no part of the claimed design.
